ATTORNEY

UNITED STATES PATENT OFFICE.

FREDERICK D. WILSON, OF MOLINE, ILLINOIS, ASSIGNEE, BY MESNE ASSIGNMENTS, TO AUSTIN MANUFACTURING COMPANY, OF CHICAGO, ILLINOIS, A CORPORATION OF ILLINOIS.

TRACTOR.

Application filed November 24, 1919. Serial No. 340,206.

To all whom it may concern:

Be it known that I, FREDERICK D. WILSON, a citizen of the United States, residing at Moline, in the county of Rock Island and 5 State of Illinois, have invented certain new and useful Improvements in Tractors, of which the following is a specification.

My invention has reference to tractors, such as are employed for general field work 10 and other work upon a farm, and it relates more specially to means for controlling the action of the tractor, either while the operator is stationed on the machine itself, on a machine being trailed in rear thereof, or 15 from a point on the ground. It also pertains to four-wheel tractors, of that class wherein the carrying-wheels are always held in line with the line of movement of the machine, the operation of turning the tractor 20 being accomplished by driving the carrying-wheels on one side of the machine, while the movement of those on the opposite side of the machine is temporarily interrupted. The 25 device also contains improvements on a similar machine for which Letters Patent of the United States were applied for by myself under date of February 4th, 1919, Serial No. 274,911, wherein the carrying wheels on opposite sides of the tractor were operatively 30 united, by means of sprocket gearing.

In devices of the class mentioned, in the 35 operation of which it is necessary to describe curves and angular turns, it is essential that the machine should respond promptly to the demands made upon it, and that the controlling mechanism should be arranged so as to act quickly and positively, and at the same time not interfere with the ordinary 40 action of the machine. One of the objects of my invention is to increase the efficiency thereof along these lines.

In carrying out the purposes of the invention I make use of novel transmission devices whereby the power of a main drive- 45 shaft may be communicated to carrying-wheels on opposite sides of the machine, to give the required movement thereto. These devices comprise two separate and independent mechanisms, not connected by 50 means of differential gearing or other devices through which one set of the transmission gearing might be affected by the action of the other set thereof. Tractors of the four-wheel drive types are quite generally 55 provided with differential gearing,

one of the results of which is that when the carrying wheel at one end of the driving axle is stopped, and the opposite wheel continues to operate, it does so at an increased rate of speed, requiring additional power to 60 drive the same. In my machine, on the contrary, the stopping of one of the carrying wheels not only does not tend to increase the speed of the active one, but permits additional power to be applied thereto, the cessation 65 of movement of the one wheel operating at once to relieve the motor from that part of its load.

I also provide novel devices for the control of the transmission mechanism, whereby the parts thereof may be operated in unison, to cause the propulsion of the machine in a direct line, or separately, to cause the same to execute a turn in either direction, or to entirely stop the same. These 75 latter devices are arranged so that they may be controlled by a pair of lines, if desired, so that the machine can be driven from a point distant therefrom, much after the manner of controlling a horse. 80

The transmission devices are of such a character that when one set thereof is thrown out of operation, the carrying wheel connected therewith is instantly locked from further movement, resulting in the turning 85 movement of the machine being quickly accomplished.

The above, and other features and advantages of my invention will more fully appear from the following specification, reference being had to the drawings accompanying the same, in which:

Fig. 1 is plan view, illustrating so much of the device as is involved in the present improvement.

Fig. 2 is an enlarged plan view of the transmission devices, with parts of the enclosing casing in section.

Fig. 3 is a side elevation of the invention.

Fig. 4 shows the clutch devices, detached 100

Fig. 5 is a detail of the steering-wheel stem and cam.

Corresponding parts are indicated by similar reference characters throughout the several figures.

The transmission devices are housed in a 105 casing, comprising a central portion 1, having an enlargement 2 and side casings 3 and 4, communicating with the central casing by means of tubular portions 5 and 6. Cen- 110

trally mounted in the casings 3 and 4 and rigidly connected therewith is an axle 7, upon the ends of which are rotatably mounted the rear carrying wheels. (Not shown herein.) The central casing and tubular extensions thereof are preferably formed in two similar sections, for the convenience of manufacture, and so that such parts will be interchangeable.

10 Rotatable on the axle 7, within the casings 3 and 4, respectively, are gear-wheels 8 and 9, (Fig. 2) provided on their outer faces with extensions 10, which have a rigid connection with sprocket-wheels 11, only one 15 of which is shown, secured to the hubs 12 of the carrying-wheels. By this means the rotary movement of the wheels 8 and 9 is imparted to the rear carrying wheels, causing the same to revolve. Movement can 20 also be communicated to the forward carrying wheels of the machine by means of sprocket chains connecting the wheels 11 with similar wheels on the hubs of the front carrying wheels. All of the carrying wheels 25 are thus utilized for the purpose of driving the machine.

Journalized in the lower part of the casing 1, at right angles with the shaft 7, is a shaft 13, operatively connected with a drive-shaft 30 14, which receives movement from the motor of the tractor. In opposite ends of the casing 1 worm drive wheels 15 and 16 are mounted on the shaft 13, so as to rotate freely thereon, said worm-drives being in 35 mesh with worm gears 17 and 18 on the ends of shafts 19 and 20 journaled in the tubular casings 5 and 6. On the outer ends of said shafts are gear pinions 21 and 22 in mesh with the wheels 8 and 9. Connected 40 with the worms 15 and 16, so as to have rotation therewith, are clutch members 23 and 24, provided with friction disks which are adapted to be engaged by similar disks contained in clutch members 25 and 26, slidably 45 on a squared portion 27 of the shaft 13. On their inner faces the last-named clutch members have bearing collars 28 and 29, against which force is applied to cause an engagement of the clutches by means of cams 30 and 31 on the lower ends of rods 32 and 33, 50 provided on their upper ends with curved extensions 34 and 35. The engagement of either of the clutch devices operates to rotate the worm associated therewith, which movement is imparted through the worm-gears and other gearing to the carrying wheels on one or other side of the machine. The engagement of both of the clutches at the same time serves to operate all of the carrying- 55 wheels simultaneously.

Suitably mounted on the frame of the tractor, convenient to the mechanism hereinbefore described, is a standard 36, in the upper end of which is pivoted a pin 37, projected downwardly into a cam 38, provided

in its lower edge with a notch 39, engaged by a dog 40, pivoted in the support 36. The dog 40 has a weighted arm 41, which tends to hold said dog in place in the notch 39, and return it thereto, upon having been displaced. By the engagement of said dog and slot the stem 37 is held normally in a vertical position.

Having a pivotal mounting on the stem 37 is a wheel 42, provided with a handle 43, 75 which is preferably hinged to the wheel, so as to fold downwardly out of the way, as indicated in broken lines in Fig. 1. On the lower face of the wheel 42 are loops 44 and 45, with which are connected the ends of rods 46 and 47, the other ends of said rods having a yieldable attachment with the ends of the arms 34 and 35 by means of frames 48 and 49, connected with the ends of said arms, and containing coiled springs 50 and 51, held on the rods 46 and 47 by means of heads or nuts on the ends thereof. When the stem 37 is vertical, and the wheel 42 in a neutral position, as shown in Fig. 1, the arms 34 and 35 will be held so as to cause 80 both of the cams 30 and 31 to operate, resulting in the movement of the carrying wheels on both sides of the machine. If it is desired to turn the machine to the right, the wheel 42 is given a slight turn in that 85 direction, this action contracting the spring 50 and holding the cam 30 in engagement with the collar 28. At the same time the spring 51 is relaxed, and the head of the rod 47 comes in contact with the frame 49, moving the arm 35 so as to disengage the cam 31. The wheels on the right hand side of the machine thereby cease to operate, while the continuation of the movement on the opposite side of the machine serves to direct 90 the movement of the machine towards the right. In this way the tractor is capable of making a rectangular turn, which is frequently required of it in its work in the field. The turning of the wheel 42 to the left will 95 cause a similar operation of the machine in that direction.

In the foregoing description of the operation of the machine it is assumed that the driver is in proximity to the wheel 42, so as to 100 operate the same with his hands, but in order that it may be actuated from a machine in rear of the tractor, or at some other point distant therefrom, said wheel is made in the form of a sheave, so as to receive a 105 cord 52 which passes around the wheel and projects rearwardly into a pair of lines, for manipulation by the hands of the operator. The lower part of the wheel is provided with a flange 42^a, to better support the lines 110 in all the positions which the wheel assumes. In operation, the wheel 42 is turned in either direction, as desired, the same as by the hands in the first instance. It frequently happens that the operator will be at one side 115

of the tractor, so that the lines, instead of extending directly to the rear, will be at one side or other of the wheel. In order that engagement of the lines with the wheel may be assured under all conditions, there is pivoted on the stem 37, above the journal of the wheel 42 a sleeve 53, carrying a guide-frame 54, the ends of which curve downwardly and enclose the cord 52, to prevent its escape from the wheel. If the driver changes his position with relation to the line of movement of the tractor, the frame accommodates it to the differing positions of the lines. It is thus possible for the operator to describe a partial circle of approximately one hundred and eighty degrees, from one side of the machine to the other. This is a special advantage when the operator is on a machine in rear of the tractor, which machine assumes different angles with relation to the tractor, such as are caused by describing curves and angles.

If it is desired to stop the tractor when in motion, the dog 40 is released from engagement with the cam 38, permitting the wheel 42 to tilt in the direction of the rods 32 and 33. This releases the tension on the arms 34 and 35, disengaging the cams 30 and 31, and interrupting the movement of the transmission devices. When it is desired to start the machine again the wheel 42 is pulled back into a horizontal position, the dog 40 automatically engaging the notch in the cam 38, and holding the wheel in such position. If the machine is being actuated by the lines, to release the cam, a quick jerk is given to the lines, causing the dog 40 to be expelled from the notch 39. The lines are then relaxed, permitting the wheel to rock forwardly. When it is desired to start the machine again the wheel is pulled back into position by means of the lines. In using the lines to stop the machine, the jerk given thereto, to release the dog, is imparted to the springs 50 and 51, causing a slight contraction thereof, and upon the wheel tipping in a forward direction there is a reaction, which is likely to be directed against the ends of the frames 48 and 49, and received upon the ends of the arms 34 and 35. In order that this action may not be too abrupt, I prefer to leave a little space between the ends of the rods 46 and 47 at the ends of the frames, when such parts are in an operative position. The reactionary force of the spring is thereby expended before the head of the rod comes in contact with the end of the frame.

If the worm drives 15 and 16 are provided with the usual pitch, it will be impossible for such worms to be turned rearwardly through a reverse movement of the worm-gears 17 and 18. It follows, therefore, that whenever either of said worms is thrown out of engagement with the clutch,

the parts associated therewith, including the carrying wheels, will be locked from movement. This adds to the successful operation of the device in turning from a straight line, the turning being accomplished by the 70 wheels which are in movement.

There has been shown and described herein the preferred embodiment of my invention, it being recognized that possible changes in the form and arrangement of 75 the parts thereof may be made within the scope and spirit thereof.

What I claim and desire to secure, is:

1. In a device of the class described, a suitably mounted casing, a shaft mounted 80 therein, adapted for connection with the main drive-shaft; worm drives mounted on said shaft, so as to rotate freely thereon; an axle mounted in said casing; carrying wheels 85 on said axle, capable of independent rotation thereon; gear-wheels supported on said axle and operatively connected with said carrying-wheels; gearing connecting said worm drives with said gear-wheels; clutch devices mounted on said shaft and operatively connected with said worm drives; and means for actuating said clutch devices, to impart rotation to said worm drive devices, so as to cause a joint or separate operation thereof, as desired. 90

2. In a device of the class described, a pair of independently rotatable carrying-wheels; gear-wheels operatively connected with said carrying-wheels; a drive-shaft rotatably mounted centrally of said carrying 100 wheels; cross-shafts rotatably mounted in proximity to said drive-shaft; gear pinions on the outer ends of said cross-shafts, in mesh with said gear-wheels; worm-gear devices operatively connecting said drive-shaft and cross-shafts, and normally out of engagement with said drive-shaft; and means for causing the engagement of said drive-shaft and worm-gearing, to actuate 105 said cross-shafts simultaneously or independently, as desired. 110

3. In a device of the class described, a pair of independently rotatable carrying-wheels; gear-wheels operatively connected with said carrying wheels; a drive shaft rotatably mounted centrally of said carrying wheels; cross-shafts rotatably mounted in proximity to said drive-shaft and projected outwardly therefrom in opposite directions; gear-pinions on the outer ends of said drive-shafts, in 115 mesh with said gear-wheels; and worm gearing operatively connecting said drive-shaft and cross-shafts, normally out of engagement with said drive-shaft, and adapted to be thrown into engagement therewith to actuate 120 said cross-shafts independently or simultaneously; said worm gearing operating to lock said cross-shafts from reverse movement when out of engagement with said drive-shaft. 130

4. In combination with a drive shaft and gearing carried thereby, normally out of engagement therewith; clutch mechanism associated with said gearing and adapted to throw the same into engagement with said shaft; a tiltingly mounted steering wheel; yieldable means of connection between said wheel and said clutch mechanism; and means for holding said wheel normally in position to cause the operation of said clutch mechanism.
5. In combination with a drive-shaft and two sets of gearing associated therewith, and normally out of engagement therewith; clutch devices operatively connected with said gearing, a tiltingly mounted steering wheel; connecting members attached to said wheel and having a yieldable connection with said clutch devices; and means for holding said wheel normally in an operative position.
6. In combination with a drive-shaft and two sets of gearing operatively associated therewith; clutch devices operatively connected with said gearing; rods adapted to operate said clutch devices independently of each other; a steering wheel rotatably mounted in proximity to said rods; and connecting means between said steering wheel and said rods provided with tension devices.
7. In combination with a frame and drive-shaft mounted therein, two sets of gearing operatively connected with said drive-shaft and normally out of engagement therewith; clutch devices operatively connected with said gearing, and adapted for the operation of either set independently of the other; rods adapted for the operation of said clutch devices; a steering wheel movably mounted on said frame; connecting means between said wheel and said rods, provided with tension devices, and means for holding said wheel normally in an operative position.
8. In combination with a frame and drive-shaft mounted therein, two sets of gearing operatively connected with said shaft and normally out of engagement therewith; clutch devices operatively connected with said gearing; rods adapted for the independent operation of said clutch devices; a steering-wheel tiltingly mounted on said frame, and provided with rein-supporting means; connecting means between said steering-wheel and said rods provided with tension devices; means for holding said wheel normally in an operative position; and reins connected with said steering-wheel.
9. In a device of the class described, steering devices comprising a tiltingly mounted stem provided with a cam member; a hand-wheel rotatable on said stem; and means for engagement with said cam member to lock said stem with the wheel in operative position, said means being adapted for automatic engagement.
10. In a device of the class described, steering devices comprising a tiltingly mounted stem provided with a cam member; a hand-wheel rotatably mounted on said stem and provided with a peripheral groove; reins operable in said groove; a guide frame mounted above said wheel, to hold said reins in an operating position; and means for engagement with said cam member to hold said stem and wheel in an operative position.
11. In combination with a frame and drive shaft mounted therein; transmission devices operatively connected with said drive-shaft, and normally out of engagement therewith; clutch devices operatively associated with said transmission devices for the independent operation thereof; clutch operating members; a steering wheel tiltingly mounted on said frame; connections between said steering wheel and clutch operating members, adapted to be released upon said wheel being tilted out of a normal position; and means for holding said wheel normally in an operative position.
12. In combination with a frame and drive-shaft mounted therein; two sets of transmission devices operatively connected with said shaft and normally out of engagement therewith; clutch devices operatively associated with said transmission devices for the independent operation thereof; clutch operating members; a steering-wheel mounted tiltingly in said frame and provided with operating reins; connecting members between said steering wheel and clutch-operating rods, provided with spring devices adapted to exert a tension upon said rods when said wheel is in an operative position; and means for holding said wheel normally in an operative position; said means being releasable upon said reins being given a jerking movement.
13. In combination with a frame and carrying wheels therefor, a drive-shaft mounted in said frame; transmission devices connecting said shaft with said carrying wheels, for the independent operation thereof, and normally out of engagement with said shaft; clutch devices operatively associated with said transmission devices; clutch-operating members; a steering-wheel supporting member tiltingly mounted on said frame; a cam associated therewith and provided with dog-engaging means; a dog pivoted adjacent to said cam and adapted for engagement therewith; a steering wheel mounted on said support and provided with operating reins; and connecting means between said wheel and clutch operating members provided with tension devices; whereby one or both of said clutch devices may be actuated when said wheel is in an operative position.

position; said dog being adapted to be released upon a jerking movement being imparted to said reins.

14. In a device of the class described, a motor and two independent power transmitting mechanisms, a rotatable member mounted upon a vertically oscillatable member for controlling the distribution of power

through said transmitting mechanism and having an operative and inoperative position, said last-named member being retained in its operative position by gravity actuated means.

In testimony whereof I affix my signature.

FREDERICK D. WILSON.
